E. B. HUNDLEY

PRINTER'S FURNITURE

Filed April 16, 1924

Edwin B. Hundley
Inventor

By William L. Sonymous
His Attorney

UNITED STATES PATENT OFFICE.

EDWIN B. HUNDLEY, OF LOUISVILLE, KENTUCKY.

PRINTER'S FURNITURE.

Application filed April 16, 1924. Serial No. 706,842.

To all whom it may concern:

Be it known that I, EDWIN B. HUNDLEY, a citizen of the United States of America, residing at Louisville, in the county of Jefferson and State of Kentucky, have invented certain new and useful Improvements in Printers' Furniture, of which the following is a specification.

My invention relates to improvements in extension furniture for printers.

An important object of my invention is the provision of a device of the above mentioned description which will have the maximum of strength and rigidity and yet will be readily adjustable to different sizes.

Another object of my invention is to provide a device of this character with improved means to automatically lock the device in any desired position.

Another object of my invention is the provision of a device of this character which will be very simple in construction and inexpensive to manufacture and yet will be strong and durable in use.

Other objects and advantages of my invention will be apparent during the course of the following description.

In the accompanying drawings which form a part of this specification and wherein like numerals are employed to designate like parts throughout the several views:

Figure 1 is a perspective view of my improved device showing the same in partially extended position,

Figure 2 is a central longitudinal section therethrough,

Figure 3 is a top plan view of the male member,

Figure 4 is a top plan view of the female section,

Figure 5 is an end elevation of the same,

Figure 6 is a transverse section taken on the line 6-6 of Figure 3, and,

Figure 7 is a perspective view of the female section.

In the drawings, wherein for the purpose of illustration is shown a preferred embodiment of my invention, the numerals 1 and 2 designate the two interfitting parts of which my improved device is composed.

The section 1 has a reduced extension 3 which is adapted to be received within the shell-like member 2. This extension 3 is only slightly reduced in size to form the narrow shoulders 5 and the entire member 1 is substantially solid in form. A longi-

tudinal opening 4 may be provided centrally of said member 1 to render it light in weight, if desired, but this opening is so arranged as not to affect the strength or 60 rigidity of the member.

The section 1 is provided with the laterally extending flanges 6 formed at the top and bottom thereof. Located midway of these flanges are the narrow grooves 7 65 which communicate with the relatively wide channels 8 which are preferably arranged in parallel relation with the side walls of the section 1. The groove and the channel combine to form a groove which is T-shaped 70 in cross-section, there being one of these T-shaped grooves on each side of the section 1.

The shell like section 2 is adapted to fit over, and slidably engage the reduced extension of the member 1 and is of a size corresponding to the difference in size between the extension 3 and the main portion of the section 1. The section 2 has its sides extended to form the strips 9 which 80 are of a length to correspond to the length of the main portion of the section 1, and of a width to correspond to the distance between the lateral flanges 6. These strips 9 are adapted to be slidably received between the flanges 6, and to have their outer faces flush with the edges of the flanges. It will therefore be seen that when the two sections are interfitted, they will appear as 90 one solid block with no breaks in the surfaces thereof.

The strips 9 are provided midway their width with T-shaped tongues 10 which are composed of the parallel strips 11 connected with the strips 10 by means of the thin webs 12. These tongues are adapted to be slidably received within the grooves in the section 1, and will be retained therein against lateral movement by reason of the 95 T-shaped tongues and grooves.

The upper surface of the reduced extension 3 is provided with an inset ratchet 13 the top of which is flush with the top surface of the extension and suitable indicia 14 may be provided adjacent each tooth of 105 the ratchet for indicating the amount of extension.

The upper wall of the shell like section 2 is provided with a cut out portion 15 through which extends the pawl 16 which 110 is provided with the ratchet teeth 17 upon its under surface for engagement with the

ratchet 13 of the extension. The pawl is attached to a very flat spring 18 which is carried by the section 2 and the construction is such that the spring and pawl project but a slight and negligible distance above the surface of the section 2. This pawl may be actuated by the hand of the operator and no complicated actuating mechanism is necessary, and still a positive 10 lock is obtained which does not project beyond the surface of the furniture sufficiently to be in the way.

It can readily be seen that when the furniture is extended there will be no openings 15 or cavities, and the device will still have the qualities and rigidity of a single solid block. The extension 3, which fills the space between the two sections presents a solid surface with no breaks, and this surface is virtually 20 a continuation of the surfaces of the two sections, as there is only a slight drop from the surface of the sections, and that of the extension. This is rendered possible by the arrangement of parts which is such that 25 the shell is supported on the solid extension which strengthens it, even when extended, and the device presents substantially unbroken sides when extended.

While I have shown and described the 30 preferred embodiment of my invention, it is to be understood that various changes in the shape, size and arrangement of parts may be resorted to without departing from the spirit of my invention or the scope of the 35 subjoined claims.

Having described my device, what I claim and desire to protect by Letters Patent is:

1. A device of the character described comprising two interfitting sections which 40 when extended will present an unbroken surface of the length of one of the sections and a substantially unbroken surface to the remainder of the length of the two sections.

2. A device of the character described 45 comprising two interfitting sections, one of said sections being of shell-like formation, the other of said sections having a substantially solid, slightly reduced extension adapted to be slidably received in said shell-like section, whereby the shell-like section 50 is strengthened thereby.

3. A device of the character described comprising two interfitting sections, one of said sections being of shell-like formation, 55 the other of said sections having a substantially solid, slightly reduced extension adapted to be slidably received in said shell-like section to strengthen the same, the sides of the shell-like section being extended to 60 form longitudinally extending strips, said strips being provided with tongues adapted to engage in corresponding grooves in the other section.

4. A device of the character described 65 comprising two interfitting sections, one of

said sections being of shell-like formation and having its sides extended to form longitudinally extending strips, tongues carried by said strips and extending the entire length of the strips and of the shell-like section, and adapted to engage corresponding grooves in the other section. 70

5. A device of the character described comprising two interfitting sections, one of said sections being of shell-like formation, 75 the other of said sections being provided with a substantially solid, slightly reduced extension adapted to be slidably received in the shell-like section, said extension being provided with a ratchet inset in its surface, 80 and a spring pressed pawl carried by the shell-like section and engaging said ratchet, said pawl conforming to the general contour of the shell-like section. 85

6. A device of the character described comprising two interfitting sections, one of said sections being of shell-like formation, 90 the other of said sections being provided with a slightly reduced extension adapted to be slidably received within said shell-like section, the side walls of said shell-like portion being extended to form longitudinally 95 extending strips, the other of said sections having each of its sides provided with a pair of narrow flanges, the strips being adapted to be received therebetween, and tongues extending the entire length of said shell-like section and of said strips, and adapted to engage corresponding grooves in the side walls of the other section, and between said flanges. 100

7. A device of the character described, comprising two interfitting sections, one of said sections being provided with a slightly reduced extension, the other of said sections being of shell-like formation and being adapted to slidably receive the reduced extension, the side walls of said shell-like section being extended to form longitudinally extending strips, the sides of the other section being each provided with a pair of narrow flanges, the strips being adapted to be received therebetween, whereby a flat surface will be formed, substantially T-shaped tongues extending the entire length of the 115 shell-like section and of the strips and adapted to engage corresponding grooves in the other section between the flanges, a ratchet formed in the upper surface of the reduced extension, and a spring pressed pawl 120 carried by the shell-like section and engaging said ratchet, the spring and pawl being substantially flush with the surface of the shell-like section. 110

8. A device of the character described 125 comprising two interfitting sections, one of said sections being of shell-like formation, the other of said sections being provided with a slightly reduced extension of the length of the shell-like section and adapted 130

to be slidably received therein, the side-walls of said shell-like section being extended to form longitudinally extending strips of the length of said other section and of a width substantially equal to the width of said section, and tongues extending the entire length of said shell-like section and of said strips, interiorly thereof, and adapted to engage corresponding grooves on the side-walls of

the other section, whereby the device will always present an entirely unbroken surface to the entire length of the shell-like section and strips, and a substantially unbroken surface for the remainder of the length of the two sections.

15

In testimony whereof I affix my signature.

EDWIN B. HUNDLEY.
